United States Patent Office

Des. 191,573
Patented Oct. 17, 1961

191,573

BATHTUB ATTACHMENT

Walter Pierchalski, 353 Hazelwood Ave., Middlesex, N.J.

Filed Aug. 12, 1958, Ser. No. 52,174

Term of patent 3½ years

(Cl. D4—3)

FIG. 2

FIG. 1 is a perspective view of a bathtub attachment showing my design; and

FIG. 2 is a top plan view thereof.

The back of applicant's device is plain and unornamented while the side not shown is like the side shown.

I claim:

The ornamental design for a bathtub attachment, as shown and described.
